UNITED STATES PATENT OFFICE.

JOHN E. WINDLE, OF NORTH GRAFTON, MASSACHUSETTS.

CLOTH-DOUBLING MACHINE.

SPECIFICATION forming part of Letters Patent No. 674,229, dated May 14, 1901.

Application filed March 21, 1900. Serial No. 9,538. (No model.)

To all whom it may concern:

Be it known that I, JOHN E. WINDLE, of North Grafton, county of Worcester, State of Massachusetts, have invented an Improvement in Cloth-Doubling Machines, of which the following description, in connection with the accompanying drawings, is a specification, like characters on the drawings representing like parts.

10 This invention in cloth-doubling machines has for its object to support in a novel manner the cloth being led to the doubling devices.

In my invention I apply the cloth to be doubled upon a carriage movable outside the framework and transversely to the longitudinal axes of the feeding-rolls which take the cloth from the doubling device preparatory to winding the same. The carriage is herein 15 represented as movable upon a track secured to the outside of the frame and also upon a suitable track located at the floor, and the carriage has suitable guiding-rollers about which the cloth is passed on its way to the 20 doubling devices. By mounting the carriage outside the framework, as stated, the operator may readily lay the goods to be doubled upon said carriage, thus obviating the difficulty of reaching under the framework to 25 deposit on the carriage the goods to be folded, as in United States Patent No. 523,499, and by reason of this carriage, mounted as described, it is possible to more readily adjust the position of the cloth with relation to the 30 doubling apparatus, so that the cloth may be doubled exactly in its center and yet provide that the strain exerted upon the cloth be in the proper lines; otherwise the cloth cannot be handled and doubled uniformly. The 35 rollers in the traveling carriage are made adjustable that they may be alined correctly one with the other to insure passage of the material to be folded in a straight line.

Figure 1 of the drawings represents a right-hand side elevation of a doubling-machine embodying my invention, and Fig. 2 is a view of the machine shown in Fig. 1 looking at it from the left-hand end.

Referring to the drawings, A represents 40 the upright or side frames of the machine, secured in usual manner to the floor. The framework A has suitable stands erected

thereon to constitute supports for the holders a¹, connected, respectively, with shafts provided with toothed gears a² and a³. The gears 55 a² and a³ are engaged by like pinions a⁴ and a⁵, fast on the main shaft a⁶ of the machine, said shaft having applied to it (see Fig. 1) a suitable clutch-pulley a⁸, adapted to receive a suitable belt driven from any usual counter-shaft to rotate the shaft a⁶ when it is desired to wind the doubled cloth or other material.

It will be obvious that the invention herein described is applicable to doubling not only 60 cloth, but any textile or web-like material.

To the framework, at one side thereof, I have secured by bolts b a stand b', having an extended ear b², upon which is mounted a bar c', which corresponds with a bar designated 70 by like letter in my Patent No. 523,499, dated July 24, 1894, said bar having co-operating with it suitable rods c, which converge at the free end of the bar c' and constitute a truncated former, the bar bracing the former 75 and holding it firmly in position while the material being doubled is being drawn over the former and wound upon the winding-board C, common to my said patent.

The framework sustains suitable pressure- 80 rolls B, through which the doubled cloth is drawn by the act of winding the same on the winding-board, or it may be a roll, and the cloth between the "former" and the pressure-rolls is passed between suitable smoothing- 85 rods d, also common to my said patent.

Herein the framework is provided with suitable short tracks 2, which receive upon them suitable wheels 3, represented as grooved at their peripheries, said wheels being mounted 90 on studs extended backwardly from a suitable traveling carriage D, of a length nearly equal to the length of the side frame A of the machine, (see Fig. 1,) said carriage having at its lower end a platform d', having suitable 95 rollers d² to run on tracks d³, located on the floor, said carriage also having other suitable rollers d⁴, which contact with the sides of the frame, so that said carriage is free to be slid longitudinally of the length of the frame and 100 at right angles to the longitudinal axes of the rollers B B and also of the cloth-winding mechanism.

The carriage D has fast upon it, as herein

represented at its front edge, a suitable smoothing-board e , against which passes one side of the material e' to be doubled. The board at its front side near its upper end has attached to it by suitable screws e^2 suitable stands e^3 , and to the upper ends of each of said stands is fixed by a set-screw 4 a bearing 5 , having ears provided with adjusting devices 6 , which act upon and adjust bearings 7 , which receive (see Fig. 1) the journals 8 , extended from a guide-roll e^4 . To restrain the rotation of this guide-roll, so that more or less force may be required to turn it, thus causing it to act as a friction-roll to detain the cloth more or less as the latter is being drawn through the machine, I provide the bearing 10 at the right-hand side of the machine, Fig. 1, with a plate 12 , and I interpose between the end of the roller e^4 and said plate a friction-washer 13 , which may be of any suitable material, and I have provided a device by which to force the right-hand end of the roll e^4 against said washer to thereby determine the extent of friction, said device consisting, as herein shown, of a thumb-screw 14 , (see left of Fig. 1,) the threaded shank of which enters a threaded hole in the bearing 7 and contacts with the end of the journal 8 , entering said bearing.

Each stand e^3 has connected with it by suitable screws f suitable boxes f' , which receive the ends of a rod f^2 , under which the cloth taken from a pile of cloth laid on the platform d' of the carriage passes on its way to and over the guide-roll e^4 , said cloth leaving said guide-roll and passing behind the board e of the traveling carriage and thence passing over a tension device G , composed of a shaft g , having its ends mounted in suitable bearings g' in suitable stands fixed to the carriage D , said shaft having at one end—the left-hand end of Fig. 1—outside its bearing a locking device g^2 , shown as a plate, having suitable notches or shoulders g^3 , and thereafter said shaft has connected with it a hand-wheel g^4 , said hand-wheel being mostly broken away in Fig. 2 to show the locking-plate behind it and the locking-dog g^5 , which co-operates with said locking-plate to hold said tension device in its operative position. The tension device is further composed of arms g^6 , fixed to the shaft g and extended backwardly, as represented in Fig. 2, said arms carrying a second rod g^7 .

The tension device is shown in its operative position in the drawings; but by lifting the notched end of the locking-dog g^5 and engaging the hand-wheel and turning it in the direction of the arrow near it in Fig. 2 the bar g^7 may be swung under the shaft g to the right, thus completely removing the tension device from contact with the cloth. By a change of position of the rod g^7 with relation to the shaft g the cloth may be made to contact with more or less of the surface of the shaft g and the rod g^7 , and thereby increase the tension on the cloth. The cloth after

passing the tension device is carried over the side of and under the guide-roll h and thence to the left viewing Fig. 2 up over the former, the two selvages of the cloth being retained in the dotted line w at the right in Fig. 2, the fold of the cloth being represented by the dotted line w' , the cloth passing from the former between the rods d and between the rollers B and being connected in the usual manner to the winding board or roller. The roll h has its journals mounted in suitable adjustable boxes h' , changeable as to their position by or through suitable screws h^2 , and the journal at one end of said roller has applied to it a suitable pulley h^3 , grooved at its periphery and embraced by a friction device h^4 , shown as two concaved bars held yieldingly together by means of a spring h^5 , surrounding a screw h^6 , (see Fig. 2,) one of said concaved bars (see Fig. 2) being divided in two parts, one part being pivoted at h^7 on the other part, the freely-movable part of the bar having a device, which may be turned in one direction when it is desired to entirely release the friction from the roll h and in the other direction when it is desired to exert friction upon the said roll.

One of the shafts supporting one of the wheels 3 has a hand-wheel m , which may be turned to rotate the wheel connected with it and cause the carriage to be moved in one or the other direction upon the tracks 2 and d^3 , so that the cloth to be folded, whatever its width, said cloth having been properly applied to the rollers e^4 and h , as described, may be so placed by the adjustment of the position of the carriage as to locate the center of the width of the cloth to be doubled at exactly the proper position with relation to the position occupied by the former, its position being fixed, it will be remembered, with relation to the framework.

If the cloth should fail to run evenly, the adjusting-screws 6 and 20 , controlling, respectively, the bearings of the rollers e^4 and h , may be adjusted so that the strain upon the cloth may be exactly determined to insure a straight-line movement of the selvages of the cloth to be doubled.

Prior to my invention I am not aware that cloth or any material to be doubled has been sustained upon a carriage movable on a track outside the framework of the machine and transversely of the longitudinal axis of the winding material for the doubled cloth, and therefore I desire to claim this invention broadly, irrespective of the particular construction shown of the carriage or of the bearing-rolls mounted in the carriage.

Having fully described my invention, what I claim, and desire to secure by Letters Patent, is—

1. In a machine of the class described, means for winding doubled material, a former to double the material, and a traveling material-carrying frame mounted outside the machine-frame and movable transversely to the

longitudinal axis of the winding means, said material-carrying frame having sliding connection with the machine-frame.

2. In a machine of the class described, winding means, means for doubling the cloth, pressure-rolls located between said doubling means and said winding means, a traveling carriage mounted vertically outside of the frame of the machine and movable longitudinally of the axis of rotation of the winding means and sustaining the material to be doubled, said material-carrying frame having sliding connection with the machine-frame.

3. In a machine of the class described, means for winding doubled material, a former to double the material, and an upright traveling frame located outside of the machine-frame and movable transversely to the longitudinal axis of the winding means, said frame carrying the material to be doubled, the upright portions of said frame being supported outside the framework and having guiding-rolls over which the cloth to be doubled is stretched on its way to the doubling means.

4. In a machine of the class described, stationary doubling means, a track outside the machine-frame, and a carriage having wheels coöperating with said track, said carriage being provided with guiding-rolls, the carriage being movable longitudinally to thereby present the material to be doubled with its central line in exactly the proper position with relation to the doubling means.

5. In a machine of the class described, winding means for the doubled material, a doubling device, and a carriage movable outside the machine-frame transversely to the longitudinal axis of the winding means, said car-

riage having guiding-rollers, and means to adjust the resistance offered by said rolls in their rotation by the material being doubled.

6. In a machine of the class described, winding means for the doubled material, a doubling device, and a carriage mounted outside of the main frame and bodily movable transversely to the longitudinal axis of the winding means, said carriage having guiding-rollers, and means to adjust the ends of said rollers to enable them to guide the material in a straight path with relation to the traveling carriage.

7. In a machine of the class described, winding means for the doubled material, a doubling device, and a carriage mounted outside of the main frame and bodily movable transversely to the longitudinal axis of the winding means, said carriage having guiding-rollers, and a tension device located between said guiding-rollers and adapted to be moved to put more or less tension upon the material being doubled.

8. In a machine of the class described, a framework, means for winding material thereon, and a traveling material-carrying frame mounted outside said framework and movable transversely to the longitudinal axis of the winding means, said carrying-frame having supporting and traveling connection with the framework at one side.

In testimony whereof I have signed my name to this specification in the presence of two subscribing witnesses.

JOHN E. WINDLE.
